TREATMENT OF HYDROCARBON OILS

Gustav Egloff and Jacque C. Morrell, Chicago, Ill.,
assignors to Universal Oil Products Company,
Chicago, Ill., a corporation of Delaware

No Drawing. Application September 16, 1933,
Serial No. 689,790

6 Claims. (Cl. 196—36)

This invention relates more particularly to the refining of relatively low boiling hydrocarbon distillates at elevated temperatures, especially those resulting from the conversion of relatively high boiling hydrocarbons at elevated temperatures and pressures.

More specifically, the invention comprises subjecting hydrocarbon oil vapors mixed with steam to treatment with phosphoric acids in the presence of solid salts of metals such as, for example, the salts of aluminum, zinc, tin, copper, lead, iron, mercury, cobalt, nickel, chromium, manganese, molybdenum, vanadium, tungsten, cadmium and others, individual salts being used alone or mixed with others in various combinations which have been found suitable for producing particular treating effects.

The types of salts which are preferred according to the present process are those which have a definite oxidizing action upon hydrocarbon oil vapors under the preferred conditions of treatment in regard to temperature and pressure. As examples of such salts may be mentioned hypochlorites, permanganates, chromates and dichromates. Of the salts mentioned as utilizable, each will exert its own particular effect upon the reactions of treatment which is not equivalent to the other salts which may be used alternately, and the selection of any one for accomplishing a particular treating effect will be determined by matters of expediency and trial in respect to its effect upon the reactions.

The acids of phosphorus which are used alternatively though without identically equivalent treating action comprise those in which phosphorus has a valence of 5, and thus include the following acids, shown along with their formulas, melting points and other properties.

40 Acid	Formula	Properties
Orthophosphoric...	$H_3PO_4(P_2O_5 \cdot 3H_2O)$ ...	M. P. 38.6° C.; $\frac{1}{2} H_2O$ 213° C.
Pyrophosphoric...	$H_4P_2O_7(P_2O_5 \cdot H_2O)$ ...	M. P. 61° C.
45 Metaphosphoric...	$HPO_3(P_2O_5 \cdot H_2O)$ ...	Sublimes.

The above acids indicate from their formulas that they represent different degrees of hydration of phosphorous pentoxide, the ortho acid being the commonest and corresponding to the maximum degree of hydration. The other two acids may be formed by igniting the ortho acid at suitable temperatures and by other methods.

We have found that the acids of phosphorus enumerated above may be employed advantageously

ly in treating hydrocarbon oil vapors, particularly vapors arising from the cracking of heavy hydrocarbon oils such as those of approximate gasoline boiling range coming from fractionators of cracking plants. The treating effect of the acids is controlled and accentuated by the concurrent use of the various oxidizing metal salts mentioned and also by the use of oxygen-containing gases such as air, oxygen or ozone. The number of metal salts which may be employed in connection with the three phosphoric acids is considerable and various treating effects may be obtained by using different combinations of acids and salts along with varying proportions of steam and oxidizing gases. However, each particular combination produces its own treating effect in the case of any given type of vapors or varying types of vapors so that there is no inference that the many combinations of treating reagents are identical in their treating action.

To obtain the best results with the solid metallic salts it is usually preferable to space them by supporting them on or mixing them with relatively inert substances of a non-metallic nature such as fuller's earth, clays, bentonite, bauxite, crushed firebrick, pumice stone, etcetera, this expedient serving to expose more surface and prevent their agglomeration into masses too large for effective action. The function of the salts or mixtures thereof employed is generally more of a chemical than a catalytic nature. In the case of definitely oxidizing salts these may gradually lose their initial oxidizing ability and ultimately function in a substantially catalytic manner. The relative amount of oxidizing and catalytic action in any case will depend upon the type of oil treated and the conditions being employed.

The usual method of refining cracked distillates is to subject them to treatment with sulfuric acid and alkaline solutions, including plumbite solutions consisting of litharge dissolved in alkaline solutions in various combinations of treatment and subsequently to subject the acid treated product to redistillation usually in the presence of steam. The present invention permits the direct treatment of the hydrocarbon vapors from the cracking process, reducing the cost of reagents and eliminating the redistillation or rerunning operation, although it is within the scope of the invention to revaporize the product in a subsequent operation and subject the vapors to treatment as described.

The invention is more particularly directed to the treatment of vapors of lower boiling cracked distillates though the vapors of straight run

distillates may also be treated within the scope of the invention.

In applying the process of the invention to practice any suitable equipment may be employed which will permit contacting the mixture of hydrocarbon vapors, oxidizing gases and steam with the acids and the solid contacting or polymerizing materials; for example, a suitable tower or chamber packed with a selected mixture of oxidizing salts may be employed following the fractionator of a cracking system, the oxidizing gases and steam being introduced when used at a suitable point or points along the line of flow of the ascending or descending vapors. Similarly, any device which permits the efficient contacting of the mixture of oxidizing gases and hydrocarbon vapors undergoing treatment with the acids and the solid contact masses may be employed. The contact materials may sometimes be employed in successive strata of varying composition or supported on superimposed trays designed to produce intimate contact.

It has been found desirable to neutralize the vapors before or after condensation and to this end the vapors may be treated with ammonia gas or pass counterflow to solutions of alkalis in auxiliary neutralizing equipment or the condensed vapors may be treated with liquid alkalis such as solutions of caustic soda, ammonia, or the like, the traces of reagents and reaction products remaining being washed out with water when found necessary.

The reactions involved in treatments conducted within the scope of the invention have been observed to produce effects comparable with those produced by sulfuric acid of varying strength used after the customary methods of treatment. The amounts of phosphoric acid reagent used will vary with the character of the vapors treated from a fraction of a percent to as high as 5% or higher by weight of the oil vapors treated in cases where relatively heavy treatments are desired. The amounts of oxidizing gases and steam used in conjunction with the acids of phosphorus may also be varied to produce a wide variety of treating effects. The period during which any particular oxidizing salt will function either chemically or catalytically will also vary, some having relatively long life and being easily regenerated by simple methods and others being effective only for short periods. In some cases by proper proportioning of the oxygen in the gas-vapor mixture undergoing treatment, a balance may be struck between the loss of oxygen from the salt and its restoration by the oxygen in the mixture so that there is substantially no change in the composition of the solid contact material.

The effects produced upon oil vapors, particularly those produced from the cracking of heavy hydrocarbon oils by the use of phosphoric acids, oxidizing gases and solid contact substances characteristic of the invention are in general those of polymerization or condensation of relatively highly unsaturated hydrocarbons or their derivatives, particularly their sulfur derivatives. The net result of the treatment is thus the conversion of gum-forming and sulfur compounds into high boiling polymers or complexes which are removed by a subsequent fractionating step. Such groups of compounds deposit gums under ordinary storage conditions or when fed to the carburetor or manifold of internal combustion engines.

Various temperatures of treatment may be

employed, for example, from 250-600° F., more or less, and the pressures may be subatmospheric, atmospheric, or superatmospheric. While the results may vary with the conditions employed, the pressures and temperatures are chosen so that the hydrocarbons are treated substantially in the vapor phase.

As specific examples of the operation of the invention and of the results obtained, a California cracked distillate of approximately motor fuel boiling range may be vaporized and subjected to treatment with aqueous orthophosphoric acid (see table) of approximately 80% concentration, the vapors being mixed with small amounts of air or oxygen and steam during their passage in a downward direction through a stationary mass of fuller's earth upon which cobalt chromate has been deposited in an amount approximately equal to one-third the weight of the fuller's earth. The phosphoric acid may be used in an amount equivalent to approximately 5 pounds per barrel. Steam is used at the rate of approximately 2 pounds per barrel. The untreated product may show a gum content of approximately 450 mgs. per 100 cc. and have a reddish-brown color, with a sulfur content of approximately 0.40%. The treated product after suitable separation from spent reagents, neutralizing with alkalis and washing with water may show a gum content of approximately 22 mgs. and a color of 25 on the Saybolt scale. The sulfur content may be found to be as low as 0.1%.

In the case of a mixed Mid-Continent and West Texas cracked distillate treated with approximately the same amounts of reagents, the gum content may be reduced from 275 mgs. to 20 and the color raised from a light amber to approximately 25 on the Saybolt scale. The sulfur content may be reduced from 0.45% to about 0.15%.

The process is particularly suitable to the treatment of cracked distillates produced from California oils. In some cases the untreated distillates may contain 500 mgs. of gum and have a dark reddish color while the treated distillates may have a gum content of only 40 mgs. and a color of 25 to 30 on the Saybolt scale. The sulfur content may be reduced from 0.48% to 0.12%.

The foregoing description and examples have disclosed a process applicable to the treatment of hydrocarbon oil vapors which has a wide applicability and is capable of great variations in the methods of operation and the amounts of reagents employed. Therefore, the specific cases cited are not to be construed in a limiting sense upon the broad scope of the invention as many other modifications and examples can be given.

We claim as our invention:

1. A process for refining relatively low boiling hydrocarbon distillates, which comprises subjecting said distillates while in heated vaporous condition to the action of phosphoric acid in the presence of a solid salt of a metal capable of exerting a mild oxidizing action.

2. A process for refining relatively low boiling hydrocarbon distillates, which comprises subjecting said distillates while in heated vaporous condition to the action of phosphoric acid in the presence of steam and of a solid salt of a metal capable of exerting a mild oxidizing action.

3. A process for refining relatively low boiling cracked hydrocarbon distillates, which comprises subjecting said distillates while in heated vaporous condition to the action of phosphoric acid in the presence of a solid salt of a metal capable of exerting a mild oxidizing action.

4. A process for refining relatively low boiling hydrocarbon distillates, which comprises subjecting said distillates while in heated vaporous condition to the action of phosphoric acid in the presence of steam and of a hypochlorite of a metal. 80
5. A process for refining relatively low boiling hydrocarbon distillates, which comprises subjecting said distillates while in heated vaporous condition to the action of phosphoric acid in the presence of steam and of a permanganate of a metal. 85
6. A process for refining relatively low boiling hydrocarbon distillates, which comprises subjecting said distillates while in heated vaporous condition to the action of phosphoric acid in the presence of steam and of a chromate of a metal. 90
